UNITED STATES PATENT OFFICE.

WALTER SCOTT, OF PLAINFIELD, NEW JERSEY.

SAFETY STOPPING AND STARTING MECHANISM FOR PRINTING-MACHINES.

SPECIFICATION forming part of Letters Patent No. 361,786, dated April 26, 1887.

Application filed January 21, 1887. Serial No. 224,976. (No model.)

To all whom it may concern:

Be it known that I, WALTER SCOTT, of Plainfield, in the county of Union and State of New Jersey, have invented an Improvement in 5 Safety Stopping and Starting Mechanism for Printing-Machines, of which the following is a specification.

This invention is especially available with 10 stop-cylinder or two-revolution printing-presses; but it may be applied with the stopping devices of any printing-press or other machinery where the trip or stopping devices are operated by foot or hand power to disconnect or throw off the cylinder or other device, 15 and thereby arrest the printing or other operation.

In the drawings, Figure 1 is an elevation of 20 a portion of a printing-press with my improvements applied thereto. Fig. 2 is a partial plan of the shafts and connections, and Fig. 3 is a side elevation of the cam and its yielding point. Fig. 4 is a section at the line $x-x$ of Fig. 3. Fig. 5 is a section at the line $y-y$, Fig. 3. Fig. 6 is a separate elevation of the safety-bar and 25 rocking piece. Fig. 7 is a plan view of the same; and Fig. 8 is a diagram representing the yielding point of the cam and point of the rocking piece in contact, showing, also, the direction of movement as the parts yield and separate.

The bed of the press is shown at A, and the 30 impression-cylinder at B. C is the starting-bar, with teeth at the upper end thereof gearing into teeth upon the gear-wheel C' upon the axis of the impression-cylinder, and there is a 35 locking-bar, D, with a tooth, 2, that passes into the notch of a block upon the gear C' to hold the impression-cylinder in the proper fixed position between one impression and the next. This locking-bar is supported upon the frame 40 of the machine and raised or lowered by a cam, 3, and rack 4, that receives its motion from the foot-trip F, or other device usually provided in printing-presses. I have shown the foot-trip F as connected to the bent lever 6 and a 45 connecting-rod, 7, to the crank 8 on the shaft 9, that carries the sector or rack 4, so that when the foot is placed upon the trip F the segmental rack 4 will be moved and the cam 3 partially revolved to hold the lock-bar D, with 50 its tooth 2, in such a position as to prevent the impression-cylinder being moved. A more

full description of a device of this character will be seen in my Patents Nos. 293,678 and 298,781 issued to me.

The crank-shaft of the press is shown at G, 55 and upon this are the cams H, that act upon the rollers I, that are upon arms extending out from the starting-bar lever C', so that the starting-bar lever is vibrated by these cams at the proper time for engaging the teeth upon the starting-bar with the teeth upon the gear-wheel of the impression-cylinder.

Upon the shaft 9 is a crank, L, to which is connected one end of the safety-bar K, and this bar K is forked to pass above and below 65 the crank-shaft G, and upon this crank-shaft G is a shell or side cam, M, and upon the safety-bar K is a stud, O. The cam M is an arc of a circle, or nearly so, and the stud O, being within the cam, prevents the shaft 9 70 being turned by the action of the foot-trip except when the stud O is at the opening between the ends of the cam M. These parts have heretofore been used in printing-presses, but the press is sometimes injured or broken by 75 the end of the cam M striking upon the stud O, and this may occur even in cases where the end of the cam is pointed or wedge shaped and where the stud O is also pointed.

My present invention is made for effectually 80 preventing the risk of injury to the press under the circumstances before named; and it consists, first, in combining with the cam and safety-bar a yielding pointed stud that will cause a separation between such stud and the 85 end of the cam, should the parts accidentally come squarely together, and, second, in a yielding point to the cam that will cause the parts to separate in case of accidental contact between the cam and the stud.

The rocking piece O' is pivoted at 10 upon the safety-bar K, and there is an elongated hole in the rocking piece, into which the stud O passes, and the arm P extends out from the rocking piece O', and there are springs Q 95 acting at each side of the arm P and serving to hold the said arm P in a central position upon the safety-bar K. These springs may be either tension or compression springs. I have shown them as placed against abutments 12 100 upon arms extending out laterally from the safety-bar K. It will be now understood that

as soon as the ends of the cam M pass out of contact with the rocking piece O' the springs Q bring the said rocking piece and its arm P into a central position upon the safety-bar K, 5 and if said bar K is moved endwise in either direction at this time the end of the cam M might strike exactly upon the pointed end of the rocking piece O', in which case the said rocking piece O' will swing upon the pivot 10, compressing one of the springs Q, and in so doing the point of the rocking bar will describe an arc of a circle from the pivot 10, and thereby carry the point of the rocking piece out of contact with the point of the cam and 15 allow said cam M to move the safety-bar K and the parts connected therewith in either one direction or the other.

As an additional safeguard, I provide a pivoted end, S, to the cam M, said end S having a projecting pin or bolt, 20, passing through an ear upon the disk of the cam M, and having outside of the disk a crank-arm, 21, against which a spring, 22, operates to hold the yielding point S of the cam in a normal position, and a stop, 24, limits the movement of the cam end S under the expansive action of the spring; but should the point of the cam end S strike directly upon the pointed end of the rocking piece O', or upon the stud 25 O, if that alone be used, then the cam end S swings upon its pivot-bolt 20, the spring 22 is partially compressed, and the point of the cam end S yields and describes an arc of a circle from the pivot 20, so that the point of the 30 cam end moves across the stud or rocking piece and the said stud or rocking piece passes either at one side or the other of the cam M, and there is no possibility for the motion being obstructed and the parts broken.

Upon reference to Fig. 8 it will be seen that the arc described by the point of the yielding stud coincides more nearly with the radial line than does the arc described by the yielding point of the cam. For this reason the 40 two yielding points will separate in describing their respective arcs should they ever come together exactly end to end, and thereby injury will be prevented by the points clearing each other. The springs also may be of different strengths.

It will be noticed that the rocking piece O' is pointed in both directions and that two springs Q are employed to bring the parts central. This is preferable, because it prevents injury to the parts when the press is being turned back by hand; but the two points to the rocking piece are not always necessary, as the force employed in turning the press backwardly by hand is seldom sufficient to 50 injure any of the parts.

It is preferable to locate the pivot of the rocking stud in the position shown; but the action will be the same if the pivot is toward the shaft instead of away from the same.

The action of the parts will be the same 65 whether my improvements are applied to a stop-cylinder printing-press, as illustrated in the drawings, or to a two-revolution printing-press in which the cylinder is raised and kept out of contact with the type-bed to prevent 70 an impression being taken, and my improvements may be used wherever available.

I claim as my invention—

1. The combination, with the safety-bar K and cam M in the starting and stopping mechanism, of a rocking stud, O', a pivot, 10, to connect the same to the safety-bar, an arm extending out from the rocking stud, and a spring acting upon the arm to swing the rocking piece upon its pivot, substantially as and for 80 the purposes set forth. 75

2. The combination, with the safety-bar K and cam M in the starting and stopping mechanism, of the rocking piece O', having two pointed ends, the arm P, carrying said rocking 85 piece, the pivot 10, connecting the parts to the bar K, and the springs Q, acting in opposite directions to move the arm and rocking piece into a central position, substantially as set forth. 90

3. The combination, with the safety-bar and its stud in the stopping mechanism, of the cam M, having a yielding end to the cam, a pivot upon which the yielding cam end S swings, and a spring to return the yielding cam end to its 95 normal position, substantially as set forth.

4. The combination, with the safety-bar K, of the rocking piece O', arm P, pivot 10, upon which the rocking piece swings, the stud O within an elongated hole in the rocking piece, 100 the cam M, the yielding cam end S, the pivot 20, the arm 21, and spring 22, substantially as and for the purposes set forth.

5. The combination, with the cam and a pivoted yielding end to the cam, of a supply-bar moving endwise, and a yielding rocking stud upon the same, the arc described by the yielding end of the rocking stud being different from the arc described by the yielding end of the cam, so that the two parts separate 105 while moving, substantially as set forth.

Signed by me this 11th day of January, 1887.

WALTER SCOTT.
